UNITED STATES PATENT OFFICE

HENRY E. KEHDER, OF HUEY, ILLINOIS

VALVE-TRUING MACHINE

Application filed April 7, 1927. Serial No. 181,854.

This invention relates to improvements in valve grinding machines, the object of the invention being to provide an improved machine which is especially adapted for use in truing internal combustion engine valves and for other similar uses.

A special object of the invention is to provide an improved machine of this kind which is compact, simple in construction, strong and durable, and which may be very readily operated either manually or by power.

Another object is to provide a machine of this kind including a bearing for a valve stem, which bearing may be readily opened to permit the ready mounting or removal of a valve stem.

Another object is to provide means for adjusting or moving the valve during the grinding operation.

With the above and other objects in view, the invention consists in the construction, combination and arrangement of devices hereinafter described and claimed.

25 In the accompanying drawings

Figure 1 is a plan of a valve grinding machine constructed and arranged in accordance with my invention and showing the same in connection with an internal combustion engine valve arranged to be ground by the machine.

Figure 2 is a vertical transverse sectional view of the same on the planes indicated by the line 2—2 of Figure 1.

25 Figure 3 is a front elevation of the same.

Figure 4 is a detail vertical sectional view on the plane indicated by the line 4—4 of Figure 3.

Figure 5 is a detail end elevation, showing the driving gears.

In the embodiment of my invention I provide a bed or base 1 from which rises a standard or pillar 2 which is integral therewith and which is provided with a bearing 3 for a shaft 4. I also provide a pillar 5 which is detachably secured to the front side of the pillar 2 by a bolt 6 and the lower end of which bears on the base 1. At its upper end the pillar 5 is provided with a longitudinally extending arm 6 which projects from one side

thereof, said arm having an opening 7 to receive and permit movement of the valve. On the front side of the arm 6, at its upper portion, is a grinding blade 8 which is secured detachably in place by means of bolts 9 and which is arranged in an inclined position as shown and is provided at its lower side with a beveled cutting edge 10. A bearing jaw 11 is arranged on the front side of the upper portion of the pillar 5 and is hingedly connected thereto at its lower side, said bearing jaw having lugs 12 which extend downwardly therefrom, said pillar having forwardly extending lugs 13 against the opposing sides of which the lugs 12 bear, and a pintle rod 14 being arranged in corresponding openings with which said lugs 12, 13 are provided and said pintle rod coacting with said lugs to thus hingedly connect the bearing jaw to the pillar 5 so that said bearing 70 jaw may be closed against the pillar as shown in the drawings or may be opened therefrom and swung downwardly from the pintle rod 14 as will be understood.

The pillar 5 and bearing jaw 11 are respectively provided in their opposing sides with semi-cylindrical bearing bores 5^a, 11^a to receive the stem rod or shaft 15 of the valve 16 which is to be ground and to permit the rotation thereof and its detachment from the machine when desired.

To secure the bearing jaw 11 in closed position and permit of its ready release, I provide said jaw with a vertical notch 17 in its upper edge and the pillar 5 with a corresponding notch 18. A fastening screw 19 has one end pivotally mounted in the notch 18 by a pin 20 which extends through said notch and said screw is adapted to be turned forwardly into and to extend through and project from the front side of the notch 17 and is provided with a winged nut 21 which is threaded thereon and which may be caused to bear firmly against the front side of the upper portion of the bearing jaw 11 to securely and yet detachably lock the latter in the closed position shown in the drawings and thus keep the stem or shaft of the valve securely and yet detachably mounted in its bearing.

A screw 22 is threaded in an opening on

the outer end of the arm 6, enters the opening 7 of said arm and is concentric with the valve stem or shaft and hence is adapted to bear against the center of the valve as shown. This 5 screw is provided with a head 23 by which it may be readily turned manually to move the valve slightly endwise from time to time as may be required while grinding the valve.

Any suitable means may within the scope 10 of my invention be provided for turning the valve stem or shaft, together with the valve, to cause the latter to be cut and ground by the edge of the blade 8. For this purpose I here show a long pinion 24 on one end of the 15 shaft 4 and a power pulley 25 on the other end of said shaft and I also show a gear wheel 26 which is detachably and slidably engaged with the long pinion and which has a hub 27 through which the valve stem 15 extends, 20 said hub being provided with a set screw 28 to engage the valve stem and to thereby detachably secure said gear wheel on said valve stem.

It is thought the operation of the invention 25 will be entirely understood from the foregoing description and that it will be also understood that a number of valves may be readily and rapidly successively ground by the use of the machine, as each valve when its grinding 30 is finished can be readily released by opening the bearing member 11, whereupon the gear wheel 26 can be detached from said valve stem and secured on the stem of another valve, which last named valve stem can be then 35 mounted in the bearing 5^a, 11^a, the bearing member 11 fastened and the valve on said stem ground in the manner and by the means hereinafter described.

Having thus described my invention, I 40 claim—

A valve truing machine comprising a base having a standard provided with a bearing, a shaft mounted in said bearing and having a pinion; a pillar detachably secured to one side 45 of said standard and provided with a longitudinally extending arm projecting from one side, said arm having an opening to receive and permit movement of a valve, a bearing member detachably connected to said pillar, 50 said member and said pillar having a bearing bore in their opposing faces to receive a valve stem, a truing element secured on said arm of the pillar and arranged to engage the valve to be trued, means to adjust the valve 55 and its stem endwise during the grinding of the valve and a gear for attachment to the valve stem and in engagement with said pinion.

In witness whereof I affix my signature.

60 HENRY E. KEHDER.
